UNITED STATES PATENT OFFICE.

RALPH R. SUTHERLAND, OF LOS ANGELES, CALIFORNIA.

DESIGN FOR A COMMERCIAL WAGON.

Application filed April 1, 1929. Serial No. 30,704. Term of patent 14 years.

To all whom it may concern:

Be it known that I, RALPH R. SUTHERLAND, a citizen of the United States, residing at Los Angeles, in the county of Los Angeles and State of California, have invented a new, original, and ornamental Design for a Commercial Wagon, of which the following is a specification, reference being had to the accompanying drawing, forming part thereof.

The shading on Figure 1 indicates the colors orange and green.

I claim:

The ornamental design for a commercial wagon, as shown and described.

Signed at Los Angeles, in the county of Los Angeles, State of California, this 21st day of March, 1929.

RALPH R. SUTHERLAND.
